UNITED STATES PATENT OFFICE.

ALBERT SCHMIDT, OF FLINT, MICHIGAN, ASSIGNOR TO CHAMPION IGNITION COMPANY,
OF FLINT, MICHIGAN, A CORPORATION OF MICHIGAN.

SPARK-PLUG.

1,241,562.

Specification of Letters Patent.

Patented Oct. 2, 1917.

Application filed March 8, 1917. Serial No. 153,233.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs, of which the following is a specification, reference being had therein to the accompanying drawings.

10 The invention relates to spark-plugs and has for its primary object the obtaining of a construction in which the electrode may be detached and replaced without destroying the gas seal. It is a further object to avoid 15 the necessity of an enlarged head at the inner end of the electrode, so that the heat of combustion will be dissipated through an increasing rather than a diminishing cross-section.

20 In the drawings:

Figure 1 is a longitudinal section through a plug embodying my invention;

Fig. 2 is a similar view showing a modified construction.

25 A is the metallic casing. Within this casing is secured an insulator formed in two sections B and C, between which is placed a metallic head D. An insulator of mica or other suitable material is placed about the 30 joint between the inner and outer insulators B and C, and all of the insulators are then retained in the casing A by a flange engagement F or other suitable gas-sealing means.

The metallic head D between the insulators B and C is internally threaded, and is 35 adapted to receive a correspondingly-threaded portion G of the electrode H. The latter is provided with an inwardly-extending portion I of lesser cross-section, which passes 40 through an aperture in the inner insulator B, and outside of the outer insulator C the electrode is threaded at J for engagement with a clamping and sealing nut K. The arrangement is such that the electrode may be 45 inserted from outside of the plug and securely clamped thereto, and also at any time may be removed and replaced.

In the construction shown in Fig. 2, the 50 enlarged shank portion of the electrode extends beyond the threaded head D and engages a recess in the inner insulator B. In the construction shown in Fig. 1 the enlarged shank terminates with the threaded portion 55 which engages the head D, and an inwardly-extending portion of smaller cross-section

passes through the insulator B. Both constructions permit of readily inserting and withdrawing the electrode, and in each case the heat which is communicated to the exposed end is readily dissipated through the 60 larger cross-section of the shank.

What I claim as my invention is:—

1. In a spark plug, the combination with an insulator, of an electrode insertible through said insulator from the outer end 65 thereof, said electrode being of a diminishing cross-section from its outer to its inner end, means protected by said insulator engageable with said electrode during insertion and anchoring the latter from outward 70 movement, and cooperating means at the outer end of said electrode for clamping the same to said insulator.

2. In a spark plug, the combination of an insulator formed in outer and inner sections 75 provided with a recess therebetween, an insulator wrapping bridging the joint between said sections, a casing in which said sections are mounted and retained in fixed relation to each other, an electrode insertible through 80 said insulator from the outer end thereof, and means located in the recess between said sections for engaging said electrode during insertion to anchor the same from outward 85 movement.

3. In a spark plug, the combination of an electrode formed in outer and inner sections having a recess therebetween, an insulator wrapping for bridging the joint between said sections, a casing in which said 90 sections are mounted and held in fixed relation to each other, a threaded member in the recess between said sections, and an electrode insertible through said sections from the outer end thereof and threaded for 95 engagement with said threaded member.

4. In a spark plug, the combination of an insulator formed in outer and inner sections, an insulator wrapping bridging the joint between said sections, a casing in which 100 said sections are mounted and held in fixed relation to each other, an internally-threaded member located between said sections, and an electrode insertible through said sections having a threaded portion for engaging with 105 said threaded member, and an inwardly-projecting exposed portion of lesser section.

5. In a spark plug, the combination with an insulator, of an electrode insertible through said insulator from the outer end 110

thereof, said electrode and insulator having a shouldered engagement, and means for retaining said members in engagement.

6. In a spark plug, the combination with 5 an insulator formed in outer and inner sections with a recess therebetween and one of said sections having an inclined shoulder, a casing for securing said outer and inner sections in fixed relation to each other, an 10 electrode insertible through said insulator sections from the outer end thereof, and having an inclined shoulder for coöperating with the first mentioned shoulder, and means

in the recess between said outer and inner sections engageable with said electrode during insertion and anchoring the same from outward movement.

7. In a spark plug, the combination with 15 an insulator member, of an electrode insertible through said insulator member from the outer end thereof, and an anchor member for said electrode, said insulator having a shouldered engagement with one of said members.

In testimony whereof I affix my signature. 20
ALBERT SCHMIDT. 25
